UNITED STATES PATENT OFFICE.

WEBSTER E. JANSSEN, OF NEW YORK, N. Y.

DESIGN FOR A COMBINED PIANO CASE AND WRITING DESK.

Application filed April 24, 1928. Serial No. 26,443. Term of patent 14 years.

To all whom it may concern:

Be it known that I, WEBSTER E. JANSSEN, a citizen of the United States, residing in the borough of Manhattan, in the city and county of New York and State of New York, have invented a new, original, and ornamental Design for a Combined Piano Case and Writing Desk, of which the following is a specification, reference being had to the accompanying drawing, forming a part thereof.

The figure is a perspective view of a combined piano case and writing-desk showing my new design.

I claim:

The ornamental design for a combined piano case and writing-desk as shown.

WEBSTER E. JANSSEN.
